UNITED STATES PATENT OFFICE.

ARLINGTON MOORE, OF BOSTON, MASSACHUSETTS, ASSIGNOR TO CLARKE-MOORE CORPORATION, OF WILMINGTON, DELAWARE, A CORPORATION OF DELAWARE.

PAPER CONTAINER.

Application filed July 31, 1920, Serial No. 400,460. Renewed May 19, 1925.

The present invention relates to paper containers made of any suitable fibrous stock, whether paper or resembling paper, and particularly to the closure therefor. The 5 container may be in the form of a can with a cylindrical side wall, or in any suitable polygonal or curved form, wound or formed in any suitable way. The paper stock may be single or multiple ply, with or without 10 incorporating a binder, and the container may be coated with paraffin or the like and may have a paper cover or advertising label.

The closure of the present invention provides an effective permanent seal suitable for 15 either the top or bottom of the container, or both, and consists of a cap having a wall which may be folded together with the side wall of the container to form a bead. Besides serving to seal the container against 20 ingress of moisture and foreign matter and egress of the contents, the bead acts to grip the cap and to hold it in position substantially rigid against pressures externally of the cap or from within the container, and at the 25 same time serves to reinforce the body of the container against deformation under lateral pressures resulting from severe handling or in shipment. Where, however, it may be desirable to reinforce the support 30 of the cap furnished by the bead, particularly to insure against the longitudinal displacement of the cap under greater pressure exerted on either side of the cap, suitable means may be included in the side wall and 35 cap for this purpose such, for example, as interlocking portions formed in the side wall of the cap.

Whether or not means are included in the 40 cap and in the side wall of the container for reinforcing the support of the cap against longitudinal displacement, the closure comprises a cap having a wall folded together with the side wall of the container to form a bead, one of the walls having a hem which 45 is convoluted to form the core of the bead and the end of the other wall being secured in the bead between the core and folded portions thereof, and extending if desired to overlap the hem while the convolutions of 50 the latter may be such that the core consists of a double hem. Where the side wall is

provided with a hem convoluted to form the core of the bead, the end of the wall of the cap is secured in the bead between the core and folded portions thereof; and where the 55 wall of the cap is provided with a hem which is convoluted to form the core, the end of the side wall is similarly secured in the bead. The bead may be spaced from the cap to facilitate its formation and also to allow for 60 the inclusion of reenforcing locking means for the cap, but whether spaced from the cap or in contact therewith, the bead and the container wall reenforced by the wall of the cap provide the requisite amount of stock for 65 working under the great pressure employed in compressing and practically solidifying the bead and parts of the cap and side wall of the container, under which condition the core of the bead becomes virtually a rigid 70 mass which serves to support and reinforce the closure structure and container and to carry the stresses set up in the bead by external or internal pressures, particularly 75 those applied to the cap and transmitted to the core by the wall of the cap when the latter is secured about the core.

In the specific embodiment of the invention hereinafter described, the closure consists of a cup shaped cap having a wall adjacent the side 80 wall of the container with which it is folded together and under pressure formed into a highly compressed and practically solidified bead, the latter being spaced from the cap to facilitate its formation exteriorly to the container and also to allow for the inclusion of 85 reenforcing locking means for the cap, to preclude its longitudinal displacement. The side wall of the container is provided with a hem which is convoluted to form the core of 90 the bead, the latter consisting of the terminal portion of the hem and a portion of its doubled-back edge forming a second hem, and the end of the wall of the cap overlaps the doubled-back edge of the hem and is secured 95 in the bead between the core and folded portions of the side wall, thus effectively supporting the cap and producing substantially an hermetically sealed closure. In order to insure against the longitudinal displacement 100 of the cap under greater pressure the closure includes interlocking means formed in por-

tions of the container and cap, the side wall of the container having impressed therein an inwardly directed recess and the wall of the cap a projecting portion fitted in the recess.

5 In the accompanying drawings illustrating the preferred embodiment of the invention in application, as an example, to a cylindrical container of single ply stock having the closure constituting the present invention applied at the respective ends thereof.

10 Fig. 1 is an elevation partly in section of the container showing the closures at both ends; Fig. 2 is an enlarged sectional detail of the upper corner of the container; Fig. 3 is a view similar to Fig. 2 but showing the 15 lower corner of the container.

15 The container has a cylindrical side wall 1 of single ply stock of suitable thickness and surface finish with top and bottom openings. 20 The respective openings are each sealed by means of a closure comprising a cap 2 and a bead 3. The cap 2 has a side wall 4 which, when the cap is in position in the end opening of the container, is adjacent the side wall 1, 25 and the bead 3 is formed of folded portions of the wall 4 and side wall 1. The core 5 of the bead is formed of the convoluted hem 6 with which the side wall 1 of the container is provided and consists of the terminal portion 30 of the hem 6 and a portion 7 of the doubled-back edge thereof forming a second hem. The end 8 of the side wall of the cap overlaps the core 5 and is thus secured in the bead between the portion 7 of the doubled-back edge of the hem and the outer convoluted or folded portions of the side wall 1.

35 The parts forming the closure for the container, and more especially the bead 3, the wall 4 of the cap, and the end portion of the side wall 1, are subjected, in forming, to a 40 high pressure, preferably from 4000 to 6000 pounds per square inch, under which pressure the parts become virtually solidified and are rigidly set to permanent gage dimensions.

45 The supporting means for the cap 2, thus provided by securing its end in the bead 3, is reenforced to insure against the longitudinal displacement of the cap under pressures applied on either side thereof by including interlocking means between the bead 3 and the cap 2 formed from portions of the side wall 1 of the container and the wall 4 of the cap, and consisting of an inwardly directed recess 9 impressed in the side wall 1 and an outwardly projecting portion 10 in the wall 4 formed to fit tightly and to seat in the recess 9.

50 The closure formed as thus described provides a tight seal impenetrable to the ingress of moisture or foreign matter into the can or the egress of the contents thereof, and may be used as a top closure for a container having any suitable bottom closure, or, as illustrated in the drawings, it may be used 55 as a permanent closure for both ends of the

container, in which case the contents would be hermetically sealed.

Having thus described my invention, what I claim is:

1. In a container, a hollow member, and a closure therefor having a wall portion folded together with the wall portion of said hollow member at an end thereof to form a bead; one of said folded portions including reversely folded parts providing a double hem constituting a core; and the other of said folded portions having the end thereof secured within said bead intermediate said core and the outer convolution of the other of said folded portions. 75

2. In a container, a hollow member, and a closure therefor having a transverse portion and an outer wall portion disposed adjacent to the wall portion of said hollow member at an end thereof, and folded inwardly therewith to form a bead above said transverse portion; one of said folded portions including a reversely folded hem constituting the core of the bead; and the other of said folded portions being secured in said bead between the core and the outer part of the other of said folded portions. 80

3. In a container, a hollow member, and a closure therefor having a wall portion folded together with the wall portion of said hollow member at an end thereof to form a bead; one of said folded portions including a folded hem constituting a core; and the other of said folded portions having the end thereof secured in said bead between the core and the outer part of the other of said folded portions, and means included in said closure and the wall of said hollow member for precluding longitudinal displacement of said closure. 95

4. In a container, a hollow member, and a closure therefor having a transverse portion and an outer wall portion disposed adjacent to the wall portion of said hollow member at an end thereof; one of the inner contiguous parts of said wall portions having a recess therein receiving the other of the inner contiguous parts for precluding longitudinal displacement of said closure; and the outer contiguous parts of said wall portions being folded inwardly together to form a bead disposed in spaced relation to said transverse portion; one of said folded portions including reversely folded parts providing a double hem constituting a core; and the other of said folded portions having the end thereof secured within said bead intermediate the core and the outer part of the other of said folded portions. 110

5. In a container, a hollow member, and a closure therefor having a wall portion folded together with the wall portion of said hollow member at an end thereof; one of said folded portions including a plurality of convoluted parts terminating in a folded hem consti- 125

130

- tuting a core; and the other of said folded portions including a convoluted part disposed between said first named convoluted parts and overlapping the edge of the hem thereof.
6. In a container, a hollow member, and a closure therefor having a wall portion folded together with the wall portion of said hollow member at an end thereof; one of said folded portions including a plurality of convoluted parts terminating in a reversely folded hem constituting a core; and the other of said folded portions including a convoluted part disposed between said first named convoluted parts and overlapping the edge of the hem thereof. 15

In testimony whereof I affix my signature.
ARLINGTON MOORE.
